UNITED STATES PATENT OFFICE

155,707

DESIGN FOR A LINK FOR AN EXPANSIBLE
BRACELET OR SIMILAR ARTICLEMorris Horovitz, Providence, R. I., assignor to W & H Jewelry Company, a corporation of Rhode Island

Application June 5, 1947, Serial No. 139,463

Term of patent 3½ years

(Cl. D45—4)

To all whom it may concern:

Be it known that I, Morris Horovitz, a citizen of the United States, residing at Providence, in the county of Providence and State of Rhode Island, have invented a new, original, and ornamental Design for a Link for an Expansible Bracelet or Similar Article, of which the following is a specification, reference being had to the accompanying drawing, constituting a part thereof.

Fig. 1 is a front elevation of a link for an expapsible bracelet or similar article, showing my novel design;

Fig. 2 is a rear view; and

Fig. 3 is a side view thereof.

I claim:

The ornamental design for a link for an expapsible bracelet or similar article, substantially as shown.

MORRIS HOROVITZ.
